CLAIM

The ornamental design for an energy storage device, as shown and described.

DESCRIPTION

1. Energy storage device
- 1.1 : Perspective
- 1.2 : Perspective
- 1.3 : Perspective
- 1.4 : Front
- 1.5 : Back
- 1.6 : Left
- 1.7 : Right
- 1.8 : Top
- 1.9 : Bottom

The broken lines in the drawings illustrate portions of the energy storage device that form no part of the claimed design.
